Henry Haines,
by *H. G. Anderson* *Atty.*

UNITED STATES PATENT OFFICE.

HENRY HAINES, OF OAKLAND, CALIFORNIA.

VAULT AND SIDEWALK LIGHT.

1,361,720.

Specification of Letters Patent.

Patented Dec. 7, 1920.

Application filed May 7, 1920. Serial No. 379,542.

To all whom it may concern:

Be it known that I, HENRY HAINES, a subject of the King of Great Britain, residing at Oakland, in the county of Alameda and State of California, have invented certain new and useful Improvements in Vault and Sidewalk Lights; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to vault and sidewalk lights of the type in which pieces or sections of glass or other transparent or translucent material, constituting a lens, are contained within sockets or spaces formed usually in a metal frame. The object of the invention is to provide such lights with means that will prevent pedestrians slipping on the light, and also to prevent fracture or injury to the individual light-giving pieces or elements contained within the frame. To the accomplishment of the foregoing and such other objects as may hereinafter appear the invention consists in the features hereinafter particularly described and then sought to be clearly defined by the claims, reference being had to the accompanying drawing forming a part hereof and in which,

35 Figure 1 is a vertical section through one of the individual light-giving elements, or lens;

Fig. 2 is a top plan view of the same, circular in outline;

40 Fig. 3 is a top plan view of one of the light-giving elements, or lens, square in outline;

Fig. 4 is a perspective of one of the non-slipping studs, its elastic base and intermediate washer, the parts being separated;

Fig. 5 is a vertical section similar to Fig. 1, with the elastic base of the non-slipping stud without a reinforcing self-contained spring or resilient element.

50 In the drawing the numeral 1 designates an individual glass-light or lens of the general type usually contained within one of the sockets or cavities of which a number are usually formed in a metallic frame such as commonly employed in vaults or sidewalk lights. This light transmitting ele-

ment or lens may be either circular or square in outline or of other desired configuration. These vault or side-walk lights not infrequently constitute an element of danger to 60 pedestrians either by reason of a coating of ice or snow in the winter season, or from the surface becoming very smooth and slippery from long and constant use. At times they have been provided with studs or projections to guard against the dangers mentioned. The objection to such constructions heretofore has been that these studs form a hard and unyielding surface for the feet of pedestrians walking over the lights, and not infrequently there is a tendency of the studs to fracture the glass lights. To afford safety for the pedestrians and guard against the objections mentioned, I provide the lens or glass lights, of which one is designated 75 by the numeral 1, with a socket or cavity 2, the bottom of which is preferably inclined from its walls to its center, and in this socket or cavity is placed an elastic filler or ferrule 3 formed with a central bore 4 to receive the 80 stem 5 of a stud 6 whose top is preferably beveled from the center to its periphery. The top of this stud rests upon the top of the elastic filler so that when the stud is stepped upon the elastic filler yields and constitutes a 85 cushion for the stud so that a yielding non-slipping safety stud is afforded for the feet of the pedestrians walking over the vault or sidewalk light made up of a number of these individual light transmitting elements. The 90

elastic cushion or base thus provided for the individual lights also serves to prevent fracture or injury to the vault light in the event of any heavy object being thrown or dumped onto the light. I prefer to insert a washer 95 7, preferably of non-corrodible metal, between the under face of the top or head of the safety stud and the elastic cushion contained within the socket or cavity of the glass light, although the same is not absolutely essential. I also prefer to have a spiral spring 8 or other spring strand or strip embedded within the elastic cushion or filler as illustrated in Fig. 1 as the same will tend to prolong the life of the elastic filler 100 105 and also assist in the prompt return of the cushion or filler to its normal position after pressure on the safety stud is removed. This embedded spring reinforce however may be omitted as indicated in Fig. 5 of the 110 drawing.

I have illustrated and described the pre-

ferred form of the invention but changes can be made therein without departing from the essential features of the invention.

Having described my invention and set forth its merits what I claim is:

- 5 1. The vault-light lens formed with a cavity, an elastic filler in the cavity, and a safety stud resting upon the elastic filler which serves as a cushion for the stud. 25
- 10 2. The vault-light lens formed with a cavity, an elastic filler in the cavity and formed with a central bore, and a safety stud formed with a stem fitting the bore of the elastic filler. 30
- 15 3. The vault-light lens formed with a cavity, an elastic filler in the cavity and formed with a central bore, and a safety stud formed with a stem fitting the cavity and having a beveled head superimposed on the 20 elastic filler.

4. The vault-light lens formed with a cavity, an elastic filler for the cavity provided with a reinforcing resilient strand, and a safety stud resting upon the elastic filler which serves as a cushion for the stud. 25

5. The vault-light lens formed with a cavity, an elastic filler in the cavity and formed with a central bore, a safety stud formed with a stem fitting the cavity and having a beveled head superimposed on the 30 elastic filler, and a bearing washer interposed between the elastic filler and head of the stud.

In testimony whereof I affix my signature in presence of two witnesses.

HENRY HAINES.
